UNITED STATES PATENT OFFICE.

LUDWIG HAÜSSLER, OF PLAUE, GERMANY, ASSIGNOR TO ROBERT REINER INCORPORATED, OF WEEHAWKEN, NEW JERSEY.

AUTOMATIC BOBBIN-WINDING MACHINE.

Application filed January 18, 1922. Serial No. 528,981.

To all whom it may concern:

Be it known that I, LUDWIG HAÜSSLER, a citizen of the Republic of Germany, and a resident of Plauen, Germany, have invented certain new and useful Improvements in Automatic Bobbin-Winding Machines, of which the following is a specification.

The present invention relates to an automatic bobbin winding machine and particularly to means for transmitting oscillatory motion to the spindle carrying the thread guides.

With automatic bobbin winding machines, it is known to impart oscillatory movement to the spindle of the thread guides by crank operated gears or eccentric. When using a crank a connecting rod is always required and the latter participating in the oscillating movement produces flying masses which disturb the quiet operation of the machine when in rapid motion. On the other hand when the guides are driven through the medium of an eccentric much friction is produced, the guides easily wear out and the movement is also unquiet.

This invention has for its object to obviate these drawbacks and consists in a novel means for transmitting oscillatory motion to the spindle of the thread guides whereby the objectionable flying masses and friction are eliminated and the machine can work with a greater number of revolutions than when using the ordinary transmission means heretofore mentioned insuring the quiet uniform movement necessary for the precise winding of the bobbins.

The invention is illustrated more or less diagrammatically in the accompanying drawing, in which, Fig. 1 is an elevation; Fig. 2 a top plan view thereof with a part shown in section; and Figs. 3-6 are diagrams illustrating the operation of my machine.

Referring to the drawing more in detail *a* denotes a gear fixed to the main driving shaft *a'* of the machine and which meshes with the gears *b* fixed on the bobbin spindles *e*. The gear *a* also meshes with a gear *c* which forms part of the mechanism for transmitting oscillatory motion to the spindle of the bobbin guides. Adjustably mounted in the gear *c* is a member *f* having a hole *g* to serve as a socket.

Extending transversely of the gear *c* is the 55 spindle *k* carrying the thread guides *d* and rotatively supported at both ends of the pointed supports *n*. Embracing the spindle *k* and pivotally connected thereto by a pin *l* is a forked piece *i*. This piece is provided 60 with an arm *h* the free end of which is formed to a ball *h'* which engages the socket *g* so that when the gear *c* revolves the arm *h* will swing in a circle and through the forked piece *i* impart oscillatory motion 65 to the spindle *k* (Figs. 4 and 6). The member *f* may be displaced in the gear *c* and locked in position by a set screw *m* (Fig. 1), the displacement affording an adjustment of the socket *g* nearer to or farther 70 from its central position, in order to cause the arm *h* to describe a larger or smaller circle and thereby control the stroke of the thread guide according to the particular 75 bobbin length. There may be several thread guides on the spindle *k* according to the number of bobbin spindles used.

What I claim is:—

1. In an automatic bobbin-winding machine, the combination with a thread guide 80 spindle and a driven gear, of a member pivotally connected at one end to said spindle and fixed to the face of said gear by a universal joint, so that during the rotation of said gear, one end of said member will 85 swing in a circle around the axis of said gear and cause the other end to oscillate said guide spindle.

2. In an automatic bobbin-winding machine, the combination with a thread guide 90 spindle and a driven gear, of a member pivotally connected at one end to said spindle, a radially adjustable socket in the face of said gear, and a ball joint at the opposite end of said member borne in said socket, 95 so that during the rotation of said gear, said member will move in a conical plane and thereby cause said spindle to oscillate.

3. In an automatic bobbin-winding machine, the combination with a thread guide 100 spindle and a driven gear, of an arm formed at one end to a fork embracing said spindle and pinned thereto and at the opposite end with a ball, a socket in the face of said gear arranged away from the center thereof, and bearing said ball so that during the rotation of said gear, said arm will be caused 105 to describe a conical plane and thereby

transmit oscillatory motion to said spindle.

4. The combination with a rotary body and a spindle extending transversely to the axis of said body, of motion transmitting

means comprising a member intervening between said body and spindle and so connected thereto that as the body revolves, said member will describe a conical plane

and thereby transmit oscillatory motion to said spindle.

Signed at Weehawken, N. J., this 30th day of December, 1921.

LUDWIG HAÜSSLER.
